SANDING DEVICE

Louis R. Pritikin, West Los Angeles, Calif.

Application August 20, 1956, Serial No. 604,893

4 Claims. (Cl. 51—187)

This invention relates to a sanding block of the type used for sanding callouses and the like on the surface of the skin, although it may be used for other purposes.

A general object of this invention is the provision of a sanding block holding several pieces of sandpaper so that when one piece is worn out it can easily be torn from the block exposing a fresh piece in position for use.

Another object is to provide a sanding block of extremely simple and inexpensive construction, which may embody simply a pair of complementary sections providing pairs of jaws at the respective ends of the device, for clamping the ends of sandpaper strips.

A further object is to provide such a sanding block wherein the ends of the sandpaper strips will be drawn into the block as the sections of the block are brought together, thereby tensioning the sandpaper in the working area thereof.

Yet another object of this invention is the provision of an arrangement for supporting the sandpaper in a manner to provide a cushioning action in the sanding operation.

More specifically, the invention contemplates a sanding block embodying a recessed member having projecting curved ends around which the end portions of the sandpaper strips are drawn into a recess defined between said curved ends. A cap member, complementary to the first member, engages said ends and clamps them in the recess. In one form of the invention, a bolt extends through the cap member and threads into the recessed member. As the bolt is tightened the center portion of the recessed member is drawn toward the cap member, and at the same time tension is applied between the ends of the recessed member, whereby the latter is bowed upwardly, forcing its ends outwardly and allowing the cap member to drop further into the depression. The rough surface of the sandpaper strip grips the ends of the cap, causing ends of the strips to be drawn further into the depression, with the result that tension is developed in the strips. The upward arching of the bottom of the recessed member provides an air cushion for the usable central portion of the sandpaper.

Other objects and advantages will become apparent as the ensuing specification is read with reference to the appended drawing in which:

Fig. 1 is a side view of a sanding block with sandpaper in place ready for use;

Fig. 2 is an exploded side view showing the sanding block disassembled;

Fig. 3 is a top view showing a piece of sandpaper being torn from the block;

Fig. 4 is a sectional side view showing a modification of the sanding block.

The sanding block is comprised generally of a recessed lower member 10, and a complementary upper member (cap) 11. Member 10 normally has a flat bottom face 12 and a recess 13 in its upper side, while the lower surface 14 of member 11 is complementary to depression

2

13 and has sharpened ends 15. A bolt 17 projects through an aperture in the center of member 11 and threads into member 10. Member 10 has relatively thick end sections joined by a relatively thin medial web of sufficient flexibility so that it can be bowed from its unstressed condition shown in Fig. 2, with its normally flat bottom face 12, to its arched condition shown in Fig. 1, with a concave bottom face indicated at 12'. The end sections are inclined upwardly to provide arms for pressure-loading coaction with the end portions of sandpaper strips 18.

Sandpaper strips 18 are easily attached to the block by laying several strips along the flat face 12 with the rough surface away from face 12. The tips of the sandpaper are bent around the ends 16 of member 10 and into recess 13. Member 11 is placed over the tips of the sandpaper in recess 13 and tightened to member 10 by bolt 17. A space 19 is left between members 10 and 11 so that the tips of sandpaper 18 may be inserted between said members. As bolt 17 is tightened, the relatively thin medial section of member 10 is drawn toward member 11, but the sandpaper tips hold the ends 15 and 16 apart forcing surface 12 to bow upwardly and thereby moving the ends 16 outwardly. The outward movement of ends 16 allows member 11 to slip further into space 19, and the rough surface of the sandpaper engaging member 11 causes it to be gripped and drawn further into depression 13 with the members 10 and 11 thus placing a great deal of tension upon the strips of sandpaper. This tension causes the sandpaper to be taut across the bowed surface 12' which provides cushioning for the usable area of the sandpaper.

When a strip of sandpaper becomes worn and useless, a sharp object such as a fingernail file or pair of scissors may be inserted between the used strip and the adjacent strip and used to tear the taut strip in two. Each piece 22 of the used strip may then be neatly torn from the block by pulling it against sharpened edge 15.

A modification of the invention (Fig. 4) contemplates a U-shaped lower member 10' with a pair of outwardly curved arms 23 and normally having a flat bottom. Sandpaper strips are wrapped about the bottom of member 10' with their tips extending over the ends of arms 23. A cap member 11', complementary to the depression in the lower member 10', is forced into the depression. As it is inserted, the ends 24 of the upper member must force arms 23 apart and therefore bow the bottom upwardly providing an air cushion for the sandpaper. As ends 24 force arms 23 apart, they place downward frictional pull on the sandpaper tips and the coarse surface facing ends 24 prevents slippage, whereby these tips will be drawn into the depression along with cap member 11' resulting with tension being placed on sandpaper 18.

Sides of cap member 10' are provided with elongated depressions 25 to receive the finger tips and facilitate grasping of the cap member.

The sandpaper strips 18 are sterilized, as by treatment with ultra-violet rays, prior to packaging thereof.

The arms at the ends of the lower member are generally of crescent shape, as shown, defining inner faces which are concave and which, at the tips of the arms, are slightly convergent upwardly so as to overhang the depression, thus providing for locking the ends of the cap member into the depression, with the interposed tips of the sandpaper strips likewise locked to the sanding block. In this connection it may be noted that the invention contemplates a hard material (e. g. unplasticized synthetic resin thermoplastic material such as methyl-methacrylate) capable of developing fairly high spring loading between the arms of the lower member as to spread apart by the interposed cap member and strip tips. This spring loading causes the arms to securely grip the strip tips against the

ends of the cap member so that they cannot possibly become loosened. Thus the operative midportions of the sandpaper strip are effectively stretched between the ends of the lower member, under a tension such as to provide a cushioning action where these stretched mid-portions of the strips are slightly spaced from the bottom of the lower member due to the arching of the bottom web thereof under said tension. The cap member has rounded end faces adapted to establish secure frictional engagement with the sand coatings of said strip tips, one of said end faces being adapted to pivotally fulcrum within the concave end face of one arm and the other being adapted to exert a camming action against the tip of the other arm when subjected to pressure forcing the cap member into said depression, whereby to spread the arms and permit the cap member to enter said depression through said restricted pass, said rounded ends of the cap member becoming locked between said concave inner faces to securely mount the sandpaper strips upon said lower member.

I claim:

1. In a miniature sanding block for holding a plurality of sandpaper strips for cosmetic use: a lower member which in longitudinal section is of shallow U-form, said lower member including a medially disposed bottom web and a pair of arms projecting upwardly from the respective ends thereof and defining with said web, an elongated depression, said web being flexible and said end sections being relatively inflexible whereby said bottom member may be bowed in response to spreading end pressure applied to said arms; a cap having respective ends adapted to be related to the faces of said arms within said recess to provide pairs of jaws at the respective ends of the block, between which the ends of the sandpaper strips may be clamped; and means for applying between said lower member and cap, forces drawing said cap into said depression, causing the ends of said cap to exert a spreading action through the interposed ends of the sandpaper strips against said arms, and to thereby place the sandpaper strips under tension and to cause said lower member to bow toward said cap so as to provide a cushioning space between the stretched sandpaper strips and the bottom face of said lower member.

2. In a miniature sanding block for holding a plurality of sandpaper strips for cosmetic use: a lower member which in longitudinal section is of shallow U-form, said lower member including a medially disposed bottom web and a pair of arms projecting upwardly from the respective ends thereof and defining, with said web, an elongated depression, said web being flexible and said end sections being relatively inflexible whereby said bottom member may be bowed in response to spreading end pressure applied to said arms; a cap having respective ends adapted to be related to the faces of said arms within said recess to provide pairs of jaws at the respective ends of the block, between which the ends of the sandpaper strips may be clamped; and a connector engaged between said cap and bottom member and operable to simultaneously draw said web toward said cap while applying pressure from the ends of said cap through the interposed ends of the sandpaper strips to said arms, whereby to place the sandpaper strips under tension and to cause said lower member to bow toward said cap so as to provide a cushioning space

4
between the stretched sandpaper strips and the bottom face of said lower member.

3. In a miniature sanding block for cosmetic use: a lower member which in longitudinal section is of shallow U-form, said lower member including a medially disposed bottom web and a pair of arms projecting upwardly from the respective ends thereof and defining with said web an elongated depression, said web being flexible and said end sections being relatively inflexible whereby said bottom member may be bowed upwardly in response to spreading end pressure applied to said arms; a substantially rigid integral cap having respective ends in opposed relation to the faces of said arms within said recess to provide pairs of jaws at the respective ends of the block; a plurality of sand paper strips having ends clamped between said jaws and spacing the cap and lower member apart and having intermediate portions in opposed relation to said web; and a connector engaged between said cap and bottom member and operable to simultaneously draw said web toward said cap while applying pressure from the ends of said cap to the interposed ends of said sandpaper strips to said arms, whereby to place said sandpaper strips under tension and to cause said lower member to bow toward said cap so as to cause said bottom face to become concave, thereby providing a cushioning space between said intermediate portions of the sandpaper strips and said bottom face.

4. In a miniature sanding block for cosmetic use: a lower member which in longitudinal section is of shallow U-form, said lower member having a normally flat lower face and including a medially disposed bottom web and a pair of arms projecting upwardly from the respective ends thereof and defining with said web an elongated depression, said web being flexible and said end sections being relatively inflexible whereby said bottom member may be bowed upwardly in response to spreading end pressure applied to said arms; a substantially rigid integral cap having respective ends in opposed relation to the faces of said arms within said recess to provide pairs of jaws at the respective ends of the block; a plurality of sandpaper strips having ends clamped between said jaws and spacing the cap and lower member apart and having intermediate portions in opposed relation to said web; and a connector engaged between said cap and bottom member and operable to simultaneously draw said web toward said cap while applying pressure from the ends of said cap to the interposed ends of said sandpaper strips to said arms, whereby to place said sandpaper strips under tension and to cause said lower member to bow toward said cap so as to cause said bottom face to become concave, thereby providing a cushioning space between said intermediate portions of the sandpaper strips and said bottom face.
